MECHANISM FOR ASSEMBLING MATCH STRIPS

Filed July 1, 1927

2 Sheets-Sheet 2

Fig. 2.

UNITED STATES PATENT OFFICE.

CHARLES F. WRIGHT, OF AKRON, OHIO, ASSIGNOR TO THE DIAMOND MATCH COMPANY, OF NEW YORK, N. Y., A CORPORATION OF ILLINOIS.

MECHANISM FOR ASSEMBLING MATCH STRIPS.

Application filed July 1, 1927. Serial No. 202,783.

This invention relates to mechanism for assembling match strips, having reference more especially to mechanism for intercepting strips of matches as they are discharged from a match making machine and arranging them in an orderly manner, with the strips alternately reversed as respects the heads of the matches, which strips are intended to be subdivided into sections of proper size for use in the manufacture of match books.

In the preferred embodiment of my invention herein illustrated the match strips are ejected in succeeding pairs from a match making machine and the paired strips are alternately reversed and assembled in such manner as to facilitate their introduction in a suitable holder for subsequent transference to the match-strip supply magazine, for example, of a machine for making match books.

My invention comprises, in combination with a source of supply of match strips in succeeding pairs, a pendant guide element to which the successive pairs of match strips are delivered in a substantially horizontal position, means arranged to intercept the successive pairs of match strips, oppositely tilt the pairs in alternation and direct them to a substantially vertical position for gravitation through the guide element, with their heads pointing in opposite directions, and a collecting element arranged to receive the oppositely-disposed pairs of strips in succession.

The invention also comprises novel features of construction and combinations of parts, all of which will be hereinafter described, and the scope of the invention then be defined in the appended claims.

In the drawings—

Figure 1 is a longitudinal vertical section of match-strip assembling mechanism embodying my invention, showing its relation to the discharge station of a match making machine.

Fig. 2 is a transverse vertical section, as on the line 2—2 of Fig. 1.

Figs. 3, 4, 5 and 6 are sections of the upper end, of the vertical strip-guiding chute showing the strip tilting member in various positions.

Referring to the drawings, 10 designates a portion of the travelling endless carrier of

a machine for making match strips; and 11 designates the cam-actuated punch head operative to eject from the carrier, at the discharge station of the machine, the match strips 12 horizontally in successive pairs. At this station the longitudinal side links of the carrier are suitably guided vertically, which links are formed, as usual, with rack teeth 13 in mesh with gear wheels 14 fast on a continuously driven transverse shaft 15 having its bearings in brackets located at the respective sides of the frame structure.

Supported adjacent the discharging station by means, for example, of arms or brackets 16, is a vertically-disposed guide structure comprising, preferably, a chute 17 whereof the back wall terminates below the punches to permit the horizontal passage into the upper portion of the chute of each succeeding pair of match strips as they are ejected from the carrier by the punch head. 75 This chute depends below the lower run of the carrier and overhangs a collecting element comprising, preferably, a pair of conveyer belts 19, which pass about pulleys 20 mounted on a shaft 21 having its bearings 80 in brackets on the main frame.

The chute is preferably of tapering formation from its upper to its lower end, and is of such internal cross-section at its upper end as to permit the entry therein of match strips in substantially horizontal position, one superposed on the other, and is of such cross-section at its lower end as to permit the free discharge, in a substantially vertical or edge-wise position, of the strips from the chute to 90 the underlying conveyer, as shown.

In the upper portion of the chute, in a plane immediately below the path of discharge of the match strips from the carrier 10, is a vibratory strip-reversing element 95 comprising, preferably, a plate 22 of less width and length than the mouth of the chute, carried by a rock-shaft 23 having its bearings in the ends of the chute. Fast on one end of the shaft 23 is an arm 24 having 100 a roll 25 which extends into the undulating cam groove 26 of a face cam 27 secured to and rotatable with the driven shaft 15. The contour of the cam groove 26 is such that as each succeeding pair of match strips are 105 ejected from the carrier 10 by the punch head 11 the arm 24, and therewith the shaft 23 and plate 22, are rocked in a manner to

swing the plate to a slanting position, either to the right or to the left; that is to say, as one pair of strips are ejected from the carrier and alight on the plate the latter is tilted to the position indicated in Fig. 3, thereby directing the strips, heads downward, to the left hand side of the chute, and as the next succeeding pair of strips are ejected and alight on the plate the plate is oppositely tilted to occupy the position indicated in Fig. 6, thereby directing the strips, heads upward, to the right hand side of the chute. Hence the pairs of match strips are alternately reversed as respects the heads of the matches, and in this condition the strips gravitate to the foot of the chute and strike the upper runs of the travelling belts, the lower end of the outer wall of the chute 17 being open or cut away, as at 28, to permit the succeeding pairs of strips to be carried away from the chute by the conveyer belts.

It is to be noted that in each movement of the rapidly oscillating plate 22 to a tilted position, either to the right or left, the pair of match strips thereon are positioned with their heads or their marginal edges against one or the other side wall of the chute, as seen in Figs. 3 and 6, and that as the tilted plate returns to its normal position the strips are swung upward to a substantially vertical position since the opposing wall of the chute affords a fulcrum for the headed ends or marginal edges of the strips, as seen in Figs. 4 and 5. The rapid action of the tilting device is of distinct advantage, since it tends positively to project the strips down the chute.

The speed of the conveyer is in such timed relation to the successive ejecting strokes of the punch head 11 and the oscillatory motion of the reversing plate 22, that the match strips are positioned in close relation upon the upper runs of the conveyer, as seen in Fig. 1, which condition facilitates their manual removal and assembly in approximately measured quantities, whereof the heads of the matches of alternate pairs of strips are oppositely disposed.

It is to be understood that my invention is not limited to the particular construction herein disclosed, as the apparatus may be modified within the principle of the invention and the scope of the appended claims.

I claim—

1. The combination with means for supplying match strips, and means for ejecting successive pairs of match strips therefrom, of a pendant guide element to which the match strips are delivered in a substantially horizontal position, means arranged to intercept the successive pairs of match strips, oppositely tilt the alternate pairs and direct them to a substantially vertical position for gravitation with their heads in op-

posite directions, and a collecting element which receives the oppositely-disposed pairs of strips.

2. The combination with means for supplying match strips, and means for ejecting successive pairs of match strips therefrom, of a pendant guide element to which the match strips are delivered in a substantially horizontal position, means arranged to intercept the successive pairs of match strips, oppositely tilt the alternate pairs and direct them to a substantially vertical position for gravitation with their heads in opposite directions, and a travelling conveyer which receives the oppositely-disposed pairs of strips.

3. The combination with means for supplying match strips, and means for ejecting successive pairs of match strips therefrom, of a pendant guide element to which the match strips are delivered in a substantially horizontal position, a vibratory member arranged to intercept the successive pairs of match strips, means for vibrating said member to tilt the pairs of match strips and direct them to a substantially vertical position for gravitation with their heads in opposite directions, and a collecting element which receives the oppositely-disposed pairs of strips.

4. The combination with means for supplying match strips, and means for ejecting successive pairs of match strips therefrom, of a pendant tapering guide chute to which the match strips are delivered in a substantially horizontal position, means arranged to intercept the successive pairs of match strips, oppositely tilt the alternate pairs and direct them to a substantially vertical position for gravitation with their heads in opposite directions, and a collecting element which receives the oppositely-disposed pairs of strips.

5. The combination with means for supplying match strips, and means for ejecting successive pairs of match strips therefrom, of a pendant tapering guide chute to which the match strips are delivered in a substantially horizontal position, means arranged to intercept the successive pairs of match strips, oppositely tilt the alternate pairs and direct them to a substantially vertical position for gravitation with their heads in opposite directions, and a travelling conveyer which receives the oppositely-disposed pairs of strips.

6. The combination with means for supplying match strips, and means for ejecting successive pairs of match strips therefrom, of a pendant tapering guide chute to which the match strips are delivered in a substantially horizontal position, a vibratory member arranged to intercept the successive pairs of match strips, means for vibrating said member to tilt the pairs of match strips and di-

rect them to a substantially vertical position for gravitation with their heads in opposite directions, and a collecting element which receives the oppositely-disposed pairs of strips.

7. The combination with means for supplying match strips, and means for ejecting successive pairs of match strips therefrom, of a pendant guide element to which the 10 match strips are delivered in a substantially horizontal position, a vibratory member arranged to intercept the successive pairs of

match strips, means including an undulating cam for vibrating said member to tilt the pairs of match strips and direct them to a 15 substantially vertical position for gravitation with their heads in opposite directions, and a travelling conveyer which receives the oppositely-disposed pairs of strips.

Signed at Barberton in the county of Summit and State of Ohio this 29 day of June, 20 A. D. 1927.

CHARLES F. WRIGHT.
